DESIGN FOR A WATER PRESSURE SPRAYER

Arthur E. Thompson, Marysville, Calif.

Application September 4, 1944, Serial No. 115,210

Term of patent 14 years

(Cl. D91—1)

To all whom it may concern:

Be it known that I, Arthur E. Thompson, a citizen of the United States, residing in Marysville, in the county of Yuba and State of California, have invented a new, original, and ornamental Design for Water Pressure Sprayers, of which the following is a specification, reference being had to the accompanying drawing, forming part thereof.

Fig. 1 is a side elevational view of a water pressure sprayer showing my new design; and

Fig. 2 is a front view thereof with the hose pipe broken away for convenience of illustration.

Fig. 3 is a transverse sectional view of the handle on line 3—3 of Fig. 1.

I claim:

The ornamental design for a water pressure sprayer, substantially as shown.

ARTHUR E. THOMPSON.
